UNITED STATES PATENT OFFICE.

CLAUDE JOHNSTONE, OF ST. LOUIS, MISSOURI.

DESIGN FOR A DOLL.

60,031.

Specification for Design.

Patented Dec. 20, 1921.

Application filed August 8, 1921. Serial No. 490,801. Term of patent 14 years.

To all whom it may concern:

Be it known that I, CLAUDE JOHNSTONE, a citizen of the United States, residing in the city of St. Louis, State of Missouri, have invented a new, original, and ornamental Design for a Doll, of which the following is a specification, reference being had to the accompanying drawing, forming part thereof.

In the drawing—

Fig. 2 is a side view thereof.

The essential feature of the design resides in the particular shape and color of the head and neck of the doll. The head 1 is of the shape and color of an orange and is crowned with three orange leaves 2. The neck is surrounded by a broad blue tie 3.

I claim:

The ornamental design for a doll as shown and described.

CLAUDE JOHNSTONE.
